WIRE ROPE TWISTER

Arne C. Abrahamsen, Brooklyn, N. Y.

Application October 12, 1945, Serial No. 622,002

4 Claims. (Cl. 57—1)

1

This invention relates to improvements in devices for manually twisting or untwisting the strands of a wire rope or cable, and one of its objects is to provide a device by means of which wire rope may be clamped by the operation of a lever, and by continued pressure on the lever may be turned to untwist or twist the strands of the wire rope or cable.

Another object of the invention is to provide a device of this character, with a stationary bearing in which the twisting device may be mounted so that a left twisted wire rope or cable or a right twisted wire rope or cable may be manipulated.

With the above and other objects in view the invention comprises certain new and useful constructions, combinations and arrangements of parts, clearly described in the following specification, and fully illustrated in the drawing, in which:

Fig. 1 is a view in elevation, showing a wire rope engaged by the manual twisting tool.

Fig. 2 is a side elevation of the stationary bearing, showing the twisting device mounted therein, the lever being broken away for convenience.

Fig. 3 is an enlarged edge view, the lever being broken away.

Fig. 4 is a view partly in elevation and partly in vertical section, taken on line 4—4 of Fig. 3, looking in the direction of the arrows.

Fig. 5 is a side elevation, the lower standard being broken away.

Fig. 6 is a side elevation of the base of the twister.

Referring to the accompanying drawing 5 designates a vertical support or standard, having a base 6. On the upper end of this support the plate 7 is attached by the bolts 8.

The plate 7 is formed with integral bosses 9 and 10, which are formed with a slot 11, and the plate 7 is also formed with an upwardly extending slot 7a, which registers with the slot 11, the upper end of which widens.

The horizontal slot 11 is constructed to receive the trunnion or integral stub shaft 12 of the twister base 13, which is also formed with another trunnion or integral stub shaft 14 on the opposite side thereof. The base is also provided with bearing faces 13a and 13b which are adapted to have flush bearing against the end face of the boss 10. The base 13 is also formed with a groove 15, which extends through the stub shafts 12 and 14, which is adapted to receive a wire rope or cable.

The base 13 is formed with opposing bearings 16 and 17, which are spaced from each other to

2

provide a slot 18, in which the lower end of the lever 19 is disposed. This lever is supported on the pivot pin 20, which extends through the bearings 16 and 17 and through the lever, and is provided with a screw thread 20a to engage the bearing 16, and a head 20b to engage the bearing 17.

The lower end of the lever is formed with a lateral foot or jaw 21, which is provided with clutch teeth 21a, to engage the wire rope, indicated at R. These teeth are disposed in a convex curve and the foot or jaw 21 is offset relative to the major axis of the lever, the pivot pin and the bearings 16 and 17 being disposed to one side of the vertical plane defined by the rope receiving slot or groove 15.

The wire rope or cable to be twisted or untwisted is passed through a standard clamping device or vise 22, mounted on a stationary support 23, located at a suitable working distance from the standard 5.

By swinging the lever to the right in the position shown in Fig. 4, the lateral foot or jaw 21 will be forced into clutching relation with the rope or cable, and by continuing the movement of the lever in the same direction, the rope will be subjected to a twisting or untwisting operation, depending on whether the wire rope or cable has a right or left twist. The cable is subjected to continued twisting, by turning the entire twisting device, including the base 13 and the lever 19 in one or more complete circles on the bosses 9 and 10 of the stationary bearing support 7. By reversing the position of the twisting head and lever on this support, by withdrawing the stub shaft 12 and inserting the stub shaft 14, the device may be adapted for handling a left twisted wire rope or cable.

My invention will be found extremely useful in connection with the repair and splicing of wire cables, and enables one man to either open up the twisted strands of the wire rope or cable, or to close these strands to produce the correct lay of the strands upon the rope or cable, and to insure uniform diameter and flow of the completed cable or rope, when subject to load operations of all character.

It is understood that various changes in the details of construction, their combination and arrangement, may be made, and various materials used in carrying out the invention, as defined by the claims herein set forth.

Having described the invention, I claim as new:

1. A wire rope twister, comprising a stationary bearing, a base having a slotted stub shaft

mounted to turn in the bearing, and a lever pivoted on the base and provided with a jaw adapted to clamp a wire rope in the slotted stub shaft.

2. A wire rope twisting device, comprising a stationary bearing, a base having a slot therein to receive the wire rope to be subjected to twisting, and a lever pivoted on the base and adapted to clamp the wire rope in the slot, the base being mounted to turn in the bearing.

3. A wire rope twisting device, comprising a stationary bearing, said bearing having a vertical slot to receive a wire rope, a base having a slotted stub shaft mounted to turn in the bearing, a lever pivoted to the base and provided with a curved angular jaw formed with teeth to bite into the rope and clamp the same so that

by turning the lever and the base the rope may be twisted or untwisted.

4. A wire rope twisting device, comprising a stationary bearing having a slot therein, a vise for holding a wire rope against turning, a base having stud shafts on opposite sides thereof, either of which may be mounted in the bearing, said base having a slot intermediate of said stub shafts and said stud shafts having a wire rope receiving slot, and a lever pivoted in the slot of the base and provided with a curved angular jaw on its lower end adapted to engage a wire rope and clamp the same against turning in said slotted stub shafts and to permit of the turning of the base on said stationary bearing.

ARNE C. ABRAHAMSSEN.
